United States Patent Office

Des. 210,298
Patented Feb. 27, 1968

210,298

AMUSEMENT SLIDE

Lee A. Moulton, Fair Oaks, Calif., assignor to Super Slide
Corporation, a corporation of Nevada

Filed Sept. 26, 1966, Ser. No. 4,036

Term of patent 14 years

(Cl. D34—5)

FIG. 1.

Fig. 2.

Fig. 3.

Fig. 4

FIG. 6

FIG. 5

FIGURE 1 is a front perspective view of an amusement slide showing my new design;

FIGURE 2 is a top plan view;

FIGURE 3 is a side elevational view;

FIGURE 4 is a fragmentary sectional view, to an enlarged scale, the plane of the section being indicated by the line 4-4 in FIGURE 3;

FIGURE 5 is a front elevational view; and,

FIGURE 6 is a rear elevational view thereof.

I claim:

The ornamental design for an amusement slide, as shown.
